SHINGLE

Paul E. Williams, Ambler, Pa., assignor to Keasbey
and Mattison Company, Ambler, Pa., a corpo-
ration of Pennsylvania

Application November 29, 1949, Serial No. 129,939

1 Claim. (Cl. 108—8)

1

This invention relates to improvements in shingles of the character disclosed in United States Patent No. 2,340,038, dated January 25, 1944, and in the roofs constructed from such shingles.

A principal object of the invention is to provide an improved shingle lacking certain inherent limitations of the shingles disclosed in the aforesaid patent.

More specifically a primary object of the invention is to provide a shingle of the stated type which, when assembled with like shingles in a roof structure, will maintain a normal flat position in the assembly and will exhibit no tendency to curl upwardly at the lower exposed edges.

Another object of the invention is to provide a shingle of the stated type exhibiting a superior stability in the said assembly and affording a roof requiring a minimum of maintenance, as hereinabove more particularly described.

Still another object of the invention is to provide a shingle that may be applied to the roof structure either from left to right or vice versa as may be found expedient.

The invention resides further in certain structural details hereinabove described and illustrated in the attached drawings wherein:

Fig. 1 is a face view of a shingle made in accordance with the invention;

Fig. 2 is a face view of a section of roof constructed with shingles of the form shown in Fig. 1;

Fig. 3 is a section on the line 3—3, Fig. 2;

Figs. 4 and 5 are fragmentary sectional views corresponding to Fig. 3 and illustrating prior art;

Fig. 6 is a face view of a shingle of modified form used in the starting course;

Fig. 7 is a view in perspective of a fragment of roof wherein the shingles are applied from left to right, and

Fig. 8 is a fragmentary view in perspective showing a section of roofing applied from right to left as distinguished from the mode of application from left to right as illustrated in Fig. 7.

With reference to Fig. 1 of the drawings, the shingle therein illustrated is constructed in accordance generally with the principle disclosed in the aforesaid United States patent, but differs from the patented shingle in certain of the essential respects. In accordance with said principle, the shingle is of generally trapezoidal shape with the side edges 1 and 2 extending substantially at right angles to the lower edge 3 of the shingle. The edge 1 is of greater length than the edge

5 2 so that in general the shingle is tapered from the left side toward the right, and the upper edge 4 of the shingle is formed in the present instance on three rectilinear lines designated respectively by the reference numerals 5, 6 and 7, the lines 5 and 7 extending inwardly from the side edges 1 and 2 respectively and meeting the opposite ends of the line 6 at points 8 and 9. Each of the lines 5, 6 and 7 is inclined to the lower edge 3 of the shingle and the points 8 and 9 define positions of maximum and minimum vertical height in the shingle as measured on lines normal to the said lower edge 3. These normal lines, which are designated by the reference numerals 11 and 12, are equidistant from each other and from the proximate edges 1 and 2 as measured along the lower edge 3 so that in effect the shingle is composed of three sections designated respectively 13, 14 and 15 of equal width of which the upper edges are formed respectively by the lines 5, 6 and 7.

10 It will be apparent that this shingle conforms in general shape to the shingle illustrated in Fig. 1 of the aforesaid patent but differs as to the relative lengths of the three lines which constitute the upper edge of the shingle. This difference in the relative proportions of the sections of the shingle constitutes an element of the present invention and involves a functional distinction

3 of the shingle and somewhat above the transverse line of the holes 17, 18, 19 and 21.

This shingle is adapted for assembly with like shingles in accordance with the principle set forth in the aforesaid United States patent and as illustrated, for example, in Fig. 2 of the present drawings. In starting the shingling operation a course of starter shingles may be laid at the lower edge of the roof. These shingles may be rectangular in form but preferably are formed by cutting away the upper and lower parts of the shingle described above, as illustrated, for example, in Fig. 6. Assuming a total shingle length of twenty-four inches, the initial shingle 24 of the starter course may be twelve inches, formed by cutting in half one of the starter shingles shown in Fig. 6. The second shingle 25, and the succeeding shingles, will be the full length. The first course of shingles will then be laid directly on top of the starter course with the lower edges of the shingles flush with the lower edges of the starter shingles as illustrated in Fig. 2. The shingles of this first course will be secured in place by means of nails passed through the holes 17 and 21, these nails coming in close proximity to the upper edges of the starter shingles as indicated at 26 in Fig. 2. The initial shingle 27 of this course, as well as the second shingle 28 and the subsequent shingles, will be of full length, so that the joints between the side edges of the shingles will be staggered with respect to the joints of the starter course.

The second course will start with a part shingle 29 of one third the normal length corresponding in form to the section 13 of the full length shingle of Fig. 1, and formed by dividing one of the latter shingles along the line 11. This shingle will be secured in place by nails passed through the holes 17 and 18, it being noted that the hole 18, by reason of its location with respect to the notch 16 of the same shingle, will when in properly overlapping relation to the underlying shingle 27 of the first course register with the notch 16 of the latter shingle, whereas the hole 17 will lie in proximity to the upper edge of the said shingle 27. The starting part shingle 29 will be followed in the second course by a full shingle 30 which will be secured in place by nails passed through the holes 17 and 21 of that shingle, it being noted that the relation between the holes 21 and the notches 16 in the respective shingles is such that when the shingle 30 is in properly lapped assembly, the hole 21 thereof will register with the notch 16 of the second full shingle 28 of the first course as indicated at 31. Thus each shingle of an overlying course will have one of its retaining nails passing through the notch 16 of the immediately underlying shingle.

The advantage of this device will be clear from the sectional view of Fig. 3 wherein it will be noted that by reason of the registration of the nail hole 32 in the upper shingle 33 with the notch 34 of the lower shingle 35, the two shingles in the areas immediately intersected by the nail 36 will find a solid support one upon the other, as distinguished from the prior arrangement illustrated in Fig. 4 wherein the nails 37 in any one shingle 38 were located at a substantial distance from the upper edge 39 of the shingle 41 immediately underlying, the upper edge of the underlying shingle thereby acting as a fulcrum about which the lower exposed portion of the upper shingle 38 tends to turn upwardly whereby eventually the normal flat relation between the shingles is frequently lost by the curling up of

the said lower portion of the shingle, as illustrated in Fig. 5.

In starting the third course of shingles a part shingle consisting of the two sections 13 and 14 is used as indicated at 42, in Fig. 2. This part shingle is secured in place by nails passed through the holes 17 and 19, and in accordance with the principle set forth above the nail 19 when the part shingle is in proper position in the assembly will register with the recess 16 of the underlying shingle 30. The second shingle 43 and the subsequent shingles of the third course will be of full length and will be secured in place by nails passed through the holes 17 and 21 thereof, the nails passing through the latter holes intersecting the notches 16 of the respective underlying shingles of the second course as indicated, for example, at 44.

In starting the fourth course a full shingle 45 is used, it being noted that in this case the nail passed through the hole 21 of this starting shingle of the fourth course will also intersect the notch 16 of the underlying shingle 43 of the third course. Thus, the first and fourth courses each initiate with a full shingle, and every fourth course is a repeat course, as distinguished from the shingle form shown in Fig. 1 of the aforesaid patent which required that the order of laying be repeated in every seventh course. As a result of this modification, the starting part shingles are of materially greater width than those of the patented shingle and afford ample space for the required two securing nails. A tendency of the smaller part shingles of the prior patent to break and to become displaced from the roof assembly is thus largely avoided with the result that a roof of superior stability is afforded and maintenance charges are substantially reduced.

Another aspect of the present invention which constitutes a substantial improvement is the fact that with the shingle form and relative arrangement of nail holes described above, the shingle is adapted for starting from either the right or left hand edge of the roof, as may be expedient. This flexibility of application is illustrated in Figs. 7 and 8 which illustrate respectively the left and right hand applications. It is to be noted that in each instance the notches 22 and 23 at the sides of the shingles are effective to locate the shingles accurately with respect to each other and to bring one or other of the nail holes, as the case may be, into registration with the notch 16 of an immediately underlying shingle. It will be noted by reference to Fig. 2 that the locating notches 22 and 23 of each shingle registers with the points 8 of the two immediately underlying shingles.

While in the interests of economy, it is considered desirable to provide a nail receiving notch in the upper edges of the shingles as described above, it will be apparent that the same desirable effect may be obtained by passing at least one of the retaining nails for each shingle through an aperture formed entirely within the edges of the immediately underlying shingle. With the shingle shown in Fig. 1, for example, the notch 16 might be replaced by an aperture 46 in the same relative position with respect to the normal line 11, the guide notches 22 and 23 being relocated accordingly. Obviously, in this case, a lesser exposed area at the lower end of the shingles will be afforded and the roof would contain a larger number of shingles.

It will be understood that the shingle described above is subject to various modifications

of this character without departure from the invention.

I claim:

A shingle adapted for assembly side by side in overlapping courses with the shingles of each course in laterally staggered relation with the shingles of the adjoining courses, said shingle being generally trapezoidal in shape and of greater horizontal length than vertical height, the said height varying from side to side and there being points of maximum and minimum height located equidistant from the opposite sides of the shingle respectively and a corresponding distance from each other so that lines normal to the lower edge of the shingle and respectively intersecting the said points of maximum and minimum height will divide the shingle into three sections of equal width, and wherein the minimum height is more than one-half the maximum height, said shingle having a series of nail holes located on a common straight nailing line parallel to the bottom edge of the shingle and positioned slightly below the point of minimum height, the terminal nail holes of said series being positioned

equidistantly inwardly from the proximate side edges of the shingle, a nail recess in the upper edge of the shingle end section having the point of maximum height, said recess being perpendicularly spaced from a line normal to the shingle base from the point of maximum height at a distance equal to the distance between a terminal nail hole and its proximate side edge, said recess also being vertically aligned with a nail hole on said nailing line, and another nail hole of said series being positioned on said nailing line adjacent to the point of intersection of said nailing line and a line normal to the base from the point of minimum height and spaced from the nail hole aligned with the nailing recess a distance equal to the width of a shingle section.

PAUL E. WILLIAMS.
